UNITED STATES PATENT OFFICE

2,434,268

METHOD OF MAKING SCISSORS

William Hartkopf, East Orange, N. J.

Application June 4, 1945, Serial No. 597,523

1 Claim. (Cl. 76—104)

2

This invention relates to scissors and to the method of manufacturing same, and has for one of its objects the provision of the method and means whereby scissor blades may be punched and a shoulder provided on the blank simultaneously with the punching operation.

Another object of the invention is the manufacture of such a scissor blade blank in a single blanking and bending operation, said blank being adapted for use both as the right and left blade of the scissors.

Another object of the invention is the provision of an improved method of producing scissors in which the maximum simplicity of manufacturing operation is obtained.

Other objects and advantages will appear as the nature of the invention is better understood, the invention consisting substantially in the novel arrangement and co-relation of parts herein fully described, and illustrated in the accompanying drawings, wherein similar reference characters are used to describe corresponding parts throughout the several views, and then finally pointed out and specifically defined and indicated in the appended claim.

The disclosure made the basis for exemplifying the present inventive concept suggests a practical embodiment thereof, but the invention is not to be restricted to the exact details of this disclosure, and the latter, therefore, is to be understood from an illustrative, rather than a restrictive standpoint.

In accordance with a preferred embodiment of the inventive concept, the invention consists in the provision of a scissor blade in which a shoulder is produced simultaneously with the blanking operation of the said blade, the shoulder being so arranged as to adapt the blade to be used with a second like blade to form a pair of scissors.

In the drawings:

Figure 1 is a top plan view of the female portion of a blanking die showing a sheet of material passing therethrough from which the blanks are being formed;

Figure 2 is a longitudinal sectional view through the die, taken on line 2—2, Figure 1, and showing the male portion of the die or punch in position for blanking a scissor blade;

Figure 3 is a cross sectional view taken on line 3—3 of Figure 2;

Figure 4 is a perspective in inverted position of the blanking punch;

Figure 5 is a top plan view of a scissor blade blank;

Figure 6 is a side elevation thereof looking from the bottom of Figure 5; and

Figure 7 is a plan view of a completed pair of scissors.

5 Referring now to the drawings in detail, 10 indicates the die bed block or body having an opening 11 therein which conforms to the shape of a scissor blade to be punched. Directly above the said body and spaced therefrom by means of metal strips 12 is a die plate 13 having a cutout 14 which is of the same general contour as that of the opening 11 in the body. If desirable the die-plate opening or cutout 14 may be relieved as at 15 (see Fig. 1). The plate 13 and strips 12 may be secured to the die bed by any suitable means such as, for instance, screws 16.

The thickness and spacing of the metal strips 12 provide a passageway 17 for a sheet of material 18 from which the scissor blades are to be blanked.

10 The blanking punch 19 includes a portion 20 adapted to be secured to movable plunger 21 of a punch press by any suitable conventional means not shown. Extending from the portion 19 is 15 the cutting portion 21 having a raised or shoulder forming portion 22.

On the downward stroke of the press plunger 21 the raised punch portion 21 first contacts the metal sheet 18 and bends the corresponding area 20 of the sheet 18 downwardly as the plunger progresses to move down, the severing of the blank 23 commencing after contact between the rear or relieved portion 24 of the said punch and the sheet 18 is established, and upon further downward movement of the punch the blank 23 is completely severed from the sheet 18 and falls through the opening 11 in the die 10.

40 The above described action produces a shoulder 25 on the blade, said shoulder being placed at such an angle as to be in juxtaposed position to the angular side edge 26 of a like blade when inverted and assembled therewith to form a pair of scissors and the said scissors are in closed position. All piercing and finishing operations 45 may be performed at any suitable time after blanking.

45 From the foregoing, it will be seen that with the improved method herein described, a pair of scissors may be produced very efficiently and at 50 a low cost.

What is claimed is:

The method of forming an integral scissor blade and handle of even thickness from sheet material, which comprises the steps of placing 55 the sheet in a die, substantially uniformly de-

pressing the blade portion of said sheet in relation to the handle portion thereof to form a shoulder at the juncture of blade and handle portions, and to sever the blade portion from the sheet, then while in the same die pressing against the handle portion to sever the handle portion from the sheet while continuing to press against the blade portion until the formed integral scissor blade and handle is pressed out of the sheet, said pressed out scissor blade and handle having a shoulder which is so positioned as to adapt the blade to be used with another identical blade to form a pair of scissors.
